BIFURCATED NETHER GARMENT

Mary D. Neilson, Minneapolis, Minn.

Application July 19, 1947, Serial No. 762,126

7 Claims. (Cl. 2—224)

1

This invention relates to a garment and is directed to a garment having a portion extending downwardly from the waist together with leg portions. The portion extending downwardly from the waist may extend above the waist. The leg portions may be of any desired length.

The human body is so constructed that the legs are attached to or merge into the trunk so that there is a distinct dividing line between the legs and trunk particularly at the front of the body. This dividing line is substantially the line of the groin and in the relative movements of the legs and trunk the leg really swings about this line. The dividing line between the legs and trunk runs through the crotch close to the leg so that there is a narrow portion flat in a lateral direction which extends between the legs and could properly be called part of the trunk. The said dividing line could also be said to pass across the body substantially in the crease of the buttock. When a person stands erect there is a decided fold at the bottom of the buttocks. This is taken up when the person bends forwardly and this fold thus accommodates forward bending movement. All relative movements of the legs and trunk really take place about the above described line.

It is an object of this invention to provide a garment having a portion surrounding the body at and below the waist, which portion extends to the above mentioned line together with leg portions which are connected at their upper ends to said first mentioned portion, a fullness being provided in the garment adjacent the lower part of the buttocks which is taken up when the body bends forwardly.

It is a further object of the invention to provide a garment having a portion extending from side to side at and below the waist, said portion having a narrowed part extending through the crotch together with leg portions secured at their upper ends to said portion along lines each of which extends from a point at one side of the garment downwardly and inwardly approximately along the groin line through the crotch close to the leg laterally approximately along the fold or crease of the buttock and upwardly to said side at a point some distance below said first mentioned point.

It is also an object of the invention to provide a garment having a portion extending about the waist and downwardly therefrom closely fitting the trunk together with leg portions secured at their upper ends to said first mentioned portion along lines extending along the dividing lines between the trunk and legs about which lines the

2

relative movement between the legs and trunk takes place, said garment having a fullness adjacent the fold in the buttocks.

These and other objects and advantages of the invention will be fully set forth in the following description made in connection with the accompanying drawings in which like reference characters refer to similar parts throughout the several views and in which:

10 Fig. 1 is a perspective view showing principally the front of the garment;

Fig. 2 is a perspective view showing principally the rear of the garment;

15 Fig. 3 is a view in front elevation showing the legs of the garment distended so as to show the portion of the trunk extending through the crotch;

Fig. 4 is a plan view showing one piece of which the garment may be made;

20 Figs. 5 and 6 are views respectively of pieces from which the leg portions can be made;

Fig. 7 is a perspective view of a person wearing said garment; and

25 Fig. 8 is a perspective view of a person in a different position wearing said garment.

Referring to the drawings, particularly Figs. 1 to 3, a garment is shown comprising a portion 10

to 30 which extends about the body adjacent the waist portion and downwardly from the waist. Said garment may have a band 10a at its top provided with elastic. While portion 10 may be in one piece or divided as desired, in the embodiment of the invention illustrated it is shown as having front and rear portions connected at the sides of the garment along lines 10b. The portion 10 extends downwardly at front and rear and has a narrowed part 10c which extends through the crotch of the body. Leg portions 11 are provided which may be of any desired length. These leg portions are connected at their upper ends to portion 10 by suitable seams along the lines 11a. Each line 11a extends from a point 11b at the side of the garment preferably on line 10b downwardly and inwardly approximately along the groin line 45 of the body. Lines 11a at the front extend downwardly and inwardly at an angle of substantially 45 degrees, as shown in Fig. 1. Line 11a extends through the crotch close to the leg of the wearer, this portion being indicated as 11aa. Like 11a then extends transversely and outwardly at the rear of the garment approximately along the crease formed by the fold of the buttock. This portion is indicated as 11ab. Portion 11ab then curves upwardly to the side of the garment preferably on line 10b to a point 11c some distance

40

45

55

below the point 11b. The leg portions 11 are shown as provided with narrow bands or hems 11d at their bottoms.

While the garment could be made of pieces divided as desired, in practice the same has been efficiently made of three pieces. One of these pieces 10p forms the portion 10 of the garment. It will be seen that it has the narrowed portion 10c. This portion 10c will be disposed at the crotch and the edges 10pa will be secured to the edges 10pb along the lines 10b shown in Figs. 1 to 3. The leg portions 11p are similar and these will extend about the leg, the side edges 11pa being connected to the edges 11pb. The edges 11pc will be connected to the edge portions 10pc, shown in Fig. 4, which extend between the side edges 10pa and 10pb.

From the above description it will be seen that a garment has been produced on a theory which is 100 per cent sound. To have the dividing lines of the garment follow approximately the dividing lines between the trunk and legs is most logical. It will be seen that the lines 11a follow a sort of an upwardly extending spiral from point 11c to point 11b. There is, as above stated, a fold in the body at the buttocks when the body stands so that there should naturally be a fold or fullness in the garment at this point when the wearer is in erect position. This fullness is provided adjacent the fold of the buttocks and is clearly shown as 10d in Fig. 2. When the wearer stoops or bends this fullness is taken up just as the fold in the buttock is taken up and the said fullness in the garment thus accommodates the forward bending movement or the stooping or kneeling movement of the wearer. This is illustrated in Figs. 7 and 8. The portion 10 of the garment fits the trunk smoothly just as does the skin of the body. The leg portions of the garment keep their places at all times, the same being held up and around the garment by the front part of the portion 10 of the garment. When the body pivots back and forth and the leg bones move in their sockets there is very little or no change in the actual through-the-crotch length of the body so there is no need for any special fullness in the crotch portion 10c forwardly or rearwardly of the body. With the legs diverging, as shown by the garment in Fig. 3, the crotch portion fits the body smoothly. When the legs move together the crotch portion folds somewhat as it does in all garments. It is again pointed out that the fullness 10d adjacent the crease of the buttocks is disposed at the exact place where the body itself lengthens in the forward bending movement.

The garment described is a form-fitting one and is extremely comfortable for it fits just like a second skin. It is therefore a logical garment and is ideal for every human being, man, woman or child. The invention is applicable to most any garment having leg portions and would have particular utility in undergarments, all kinds of sport garments, slacks, trousers, etc. A suitable opening could be made in the front of the garment for men and boys without departing from the principle or inventive idea. Also in practice and for the purpose of saving material and economical construction the trunk section 10 could be pieced and reinforced if desired at the crotch and the leg sections could be divided along any chosen line as at the inner portion thereof. It is obvious that the garment could be made of any sort of material.

It will of course be understood that various

changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. A garment comprising a substantially cylindrical top portion, the upper portion of which is adapted to surround the waist of the wearer, said top portion having front and rear parts extending downwardly and connected by a narrow crotch portion, said parts extending to lines which extend from points at the sides of said garment and inwardly and downwardly at the front to and along said crotch portion and upwardly and outwardly in convex curves at the rear to points at said sides spaced below said first mentioned points respectively, said garment also comprising leg portions of general cylindrical form extending downwardly from said lines, said rear part also having a fullness extending thereacross adjacent said lines forming a fold when the wearer is in standing position but which will be taken up when the wearer bends forward, said lines at the front being adapted to extend along the groin lines of the wearer.

2. A garment having a top portion of general cylindrical form adapted to extend around the waist of the wearer and downwardly at the front and rear thereof and having a portion of reduced width forming a crotch portion, said garment also comprising leg portions secured at their upper ends to said top portion respectively along lines which extend from points respectively at the sides of said garment some distance from the upper end thereof downwardly and inwardly in concave curves at the front to and along said crotch portion and then upwardly and outwardly at the rear in convex curves to points respectively at said sides, said lines at the front being adapted to extend along the groin lines of the wearer respectively, said garment having a fullness extending across its rear adjacent the bottom of said top portion, said garment being formed to closely fit the wearer except at said fullness.

3. A garment having a top portion of general cylindrical form adapted to enclose the waist of the wearer, said portion extending downwardly at its front from the waist and through the crotch and upwardly at the rear, the same being formed to closely fit the trunk of the body at the front and back thereof except that the rear part of said garment has a fullness extending thereacross at its rear adjacent the lower end of said top portion, said garment also comprising leg portions secured to said top portion along lines which extend from points respectively at the outer sides of said garment downwardly and inwardly at the front to and through the crotch and outwardly and upwardly at the rear of said garment in convex curves to said outer sides respectively, said lines at the front being adapted to extend along the groin lines of the wearer.

4. A garment having a substantially cylindrical upper portion adapted to encircle the waist of the wearer, said portion extending downwardly at the front and rear and having a narrow crotch part extending through the crotch, said garment also comprising leg portions and having their upper ends secured to said upper portion along lines which extend from points at the outer sides of

75 said garment respectively downwardly and in-

wardly at the front to and along said crotch part and then outwardly and upwardly in convex curves at the rear to said outer sides respectively, said garment being constructed to snugly fit the trunk and leg portions of the body of the wearer with said lines at the front extending along the groin lines of the wearer, said garment also having a fullness at the rear extending across the rear thereof just above said lines at the rear, said garment being seamed at the outer sides of said top portion and leg portions.

5. A garment having a top portion having a band at its top adapted to encircle the waist of the wearer and extending downwardly from said band at the front and rear and having a narrow crotch portion, said garment also having leg portions secured to said top portion at their upper ends along lines extending from points respectively at the outer sides of said garment some distance below said band downwardly and inwardly at the front to and along the sides of said crotch portion and outwardly and then upwardly at the rear in convex curves to points some distance below said first mentioned points respectively, said garment also having a fullness extending across the rear thereof just above said lines.

6. A garment having a top portion adapted to extend about the waist portion of the wearer and having parts extending downwardly at the front and rear and connected at their outer sides, said parts being connected by a portion of reduced width extending through the crotch and forming a crotch portion, said garment comprising leg portions secured to said top portion along lines which extend from points at the outer sides respectively of said garment downwardly and inwardly at a substantially 45 degree angle at the front to and along the edge of said crotch portion and then outwardly and upwardly at the rear in convex curves to points spaced vertically from

said first mentioned points respectively, said lines at the front being adapted to extend along the groin lines of the wearer, said garment also having a fullness at the rear extending there-across just above said lines forming a fold when the wearer is standing, said lines at the rear being adapted to follow substantially the creases of the buttocks respectively of the wearer, said garment being formed to closely fit the body of the wearer except at said fullness.

7. A garment having a top portion adapted to surround the waist portion of the wearer, said portion having front and rear parts of different shapes extending downwardly from the top of said garment, said parts being connected by a narrow crotch portion, said garment comprising leg portions secured at their upper ends to said parts along lines which extend from points at the outer sides of said garment respectively, downwardly and inwardly in concave and convex curves respectively at the front and rear to substantially the center of said crotch portion at the sides thereof, said garment also having a fullness extending across said rear part adjacent said lines, said lines at the front part of said top portion being adapted to extend along the groin lines of the wearer.
